UNITED STATES PATENT OFFICE.

HARRY L. BOOK, OF HONOLULU, TERRITORY OF HAWAII.

KEYLESS LOCK.

1,297,991.

Specification of Letters Patent.

Patented Mar. 25, 1919.

Application filed September 20, 1918. Serial No. 254,990.

To all whom it may concern:

Be it known that I, HARRY L. BOOK, a citizen of the United States, residing at Honolulu, Territory of Hawaii, have invented certain new and useful Improvements in Keyless Locks, of which the following is a specification.

This invention relates to hardware, and more particularly to keyless locks.

10 The object of the invention is to provide a simply constructed and efficient lock which will reliably secure a closure and which cannot be released except by those knowing the combination.

15 Another object is to construct a lock of this character which may be cheaply manufactured and easily applied to any door.

With the foregoing and other objects in view, which will appear as the description 20 proceeds, the invention resides in the combination and arrangement of parts and in the details of construction hereinafter described and claimed, it being understood that changes in the precise embodiment of the 25 invention herein disclosed may be made within the scope of what is claimed without departing from the spirit of the invention.

In the accompanying drawings:—

Figure 1 represents an inside view of a 30 door equipped with this lock with parts broken out, the lock being shown in operative position in full lines.

Fig. 2 is a similar view taken from the outside of the door, parts being broken out 35 for convenience in illustration,

Fig. 3 is a detail section taken on the line 3—3 of Fig. 1,

Fig. 4 is a detail section taken on the line 4—4 of Fig. 1,

40 Fig. 5 is a detail perspective view of the locking bolt, and

Fig. 6 is a similar view of the bolt engaging lever.

In the embodiment illustrated, the lock 45 constituting this invention comprises a hook-shaped keeper 1 mounted on the frame F of a door, with the beak or bill of the hook turned upwardly as shown in Fig. 1. A coöperating locking bolt 2 is mounted for 50 swinging movement in the door D having a rightangular arm 3 extending through the door and forming a journal for the bolt, the outer end of said arm 3 being arranged on the outer face of the door and equipped with 55 an actuating knob 4. This bolt 2 when swung into operative position has its free

end projecting beyond the edge of the door and engaged with the keeper 1 as shown clearly in Fig. 1.

An L-shaped locking lever 5 has its short 60 arm 6 extended through the door D in a plane in advance of and above the bolt 2, its outer end, which is positioned on the outer face of the door, being provided with a knob 7, (see Fig. 2). The door D has a 65 slot 8 on its inner face arranged parallel with bolt 2 when the latter is in operative position, and which extends from the point where the lever 5 passes through the door to a point adjacent the front edge of the 70 door. This groove 8 forms a seat for the long arm 6' of the lever 5 when the latter is in inoperative position, so that it will not interfere with the releasing movement of bolt 2. 75

A plate 9 is pivotally mounted on an L-shaped pivot member 10, the short arm 11 of which extends through the door in a plane above that occupied by the lever 5 and has an actuating knob 12 on its outer end. 80 The long arm 11' of the pivot 10 extends edgewise into one end of the plate 9 and by turning the knob 12, the plate 9 may be swung upward or downward at the will of the operator and is designed for locking 85 lever 5 in operative position as shown in Fig. 1.

The plate 9 has a slot 13 extending longitudinally thereof near its free end and which is designed to receive a locking finger 90 14 carried by one end of a catch member 15. This catch member 15 extends through the door in a plane above that occupied by the pivot member 10, and its outer end is equipped with an actuating knob 16. The 95 finger 14 of the member 15 is designed to extend through the slot 13 in plate 9 when said plate is in operative position, the finger being turned at an angle to the slot after its passage therethrough to hold the plate 100 against upward or downward movement, as is shown clearly in Fig. 1.

In the operation of this lock, the parts being in the position shown in Figs. 1 and 2, when it is desired to release bolt 2 for opening the door, the locking member 15 is given a partial rotation through the knob 16 to bring the finger 14 thereof in alinement with slot 13. A pull is then exerted on knob 16 which draws the finger 14 out of engagement 110 with the plate 9, and this plate 9 may then be swung into upward position as shown in

dotted lines in Fig. 1, the swinging movement being accomplished by means of knob 12. When the plate has been raised the bolt locking lever 5 may be swung through a partial revolution until the long arm 6' thereof is disposed in seat 8. The bolt 2 may then be rotated or swung upwardly by grasping knob 4 and turning it, and this will disengage the bolt from the keeper 1 and permit 10 the door to be opened.

To lock the door, the operation above described is reversed, the bolt 2 being swung downward until its free end rests in the keeper 1. The lever 5 is then swung rearwardly until its long arm 6' rests on bolt 2 as shown in Fig. 1. Plate 9 is then swung downwardly by turning knob 12 until its lower edge rests on lever arm 6'. The knob 16 is then grasped and the member 15 moved 20 inwardly until the finger 14 carried thereby passes through slot 13 in plate 9. The knob is then turned to bring the finger into the position shown in Fig. 1, at right angles to slot 13, and when in this position, the plate line 25 is locked and cannot be turned on its pivot until the finger 14 is disengaged therefrom in the manner above described.

It will thus be seen that this lock, while very simple in construction, is thoroughly 30 efficient in operation and may be readily applied to any door already in use.

The members of this lock on the inner face of the door, may if desired, be incased in a suitable casing, not shown.

35 From the foregoing description, taken in connection with the accompanying drawings, the advantages of the construction and of the method of operation will be readily apparent to those skilled in the art to which 40 the invention appertains, and while I have described the principle of operation of the invention together with the device which I now consider to be the best embodiment thereof, I desire to have it understood that 45 the device shown is merely illustrative and that such changes may be made as are within the scope of the claimed invention.

Having thus fully described my invention, what I claim as new and desire to secure by 50 Letters Patent, is:—

1. In a lock of the class described, a bolt having an arm for extension through the

closure to be secured, and provided at its terminal with an actuating handle, a bolt locking rod for extension through the closure 55 and adapted to be swung into the path of the locking bolt, a member mounted to swing over said rod to hold it in engagement with said bolt, and a locking device for holding said member in engagement with the rod. 60

2. In a lock of the class described, a bolt having a right angular arm for extension through the closure to be secured, and provided at its terminal with an actuating handle, a bolt locking rod having a right angular arm for extension through the closure 65 and adapted to be swung into the path of the locking bolt, a member mounted to swing over said rod to hold it in engagement with said bolt, and a locking device for holding 70 said member in engagement with the rod.

3. In a lock of the class described, a bolt having a laterally extending arm with a knob at its free end, said arm being adapted to operate as a journal for the bolt, an L-shaped bolt securing member provided with a knob at the free end of one arm, said arm being adapted to operate as a journal for 75 said member, a plate pivotally mounted for engaging said member when in operative position, said plate having an aperture therein, and a locking element adapted to extend through said aperture to lock the plate in operative position.

4. In a lock of the class described, a bolt 85 having a laterally extending arm with a knob at its free end, said arm being adapted to operate as a journal for the bolt, an L-shaped bolt securing member provided with a knob at the free end of one arm, said arm 90 being adapted to operate as a journal for said member, a plate pivotally mounted for engaging said member when in operative position, said plate having an aperture therein, and a locking element having a laterally ex- 95 tendsing finger adapted to project through said aperture and to be disposed at an angle to hold the plate in locked position.

In testimony whereof I affix my signature in presence of two witnesses.

HARRY L. BOOK.
